CLAIM

The ornamental design for a headphone having a storage compartment within the headband for augmented computer glasses, as shown and described.

DESCRIPTION

FIG. 1 is a perspective view of a headphone having a storage compartment within the headband for augmented computer glasses, showing my new design in use;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is an alternate perspective of the augmented computer glasses in the down position out of the storage compartment view thereof.

The broken lines in the Figures represent unclaimed portions and form no part of the claimed design.
